UNITED STATES PATENT OFFICE.

WILLIAM H. BAIN, OF ST. LOUIS, MISSOURI.

SHOE AND PROCESS OF MAKING THE SAME.

1,264,880.

Specification of Letters Patent.

Patented May 7, 1918.

Application filed December 20, 1915. Serial No. 67,731.

To all whom it may concern:

Be it known that I, WILLIAM H. BAIN, a citizen of the United States, and a resident of the city of St. Louis and State of Missouri, have invented a new and useful Improvement in Shoes and Processes of Making the Same, of which the following is a specification.

This invention relates particularly to welt shoes, and has to do principally with the insole and shank construction of machine made welt shoes.

The object of the invention is to produce a foot-conforming shoe having a flexible arch and a close shank; and the invention consists in having the insole channeled only to the shank on the inside and using with it a shank lip or channel piece secured across the insole and inseamed to the upper and welt 20 on both sides of the shank. The invention also consists in the shape and arrangement of the insole, shank piece and inseam; and in the shoes hereinafter described as new articles of manufacture.

Further objects of the invention appear in connection with the description of the embodiment of the invention shown in the accompanying drawings; and what the invention consists in is more particularly defined 30 in the appended claims.

In the drawings, wherein the same reference characters designate similar parts in the several views,

Figure 1 is a bottom plan view of an insole suitable for use in a shoe embodying one form of the invention;

Fig. 2 is a cross-section on the line 2—2 in Fig. 1;

Figs. 3, 4 and 5 are views similar to Fig. 2, showing modified forms of insoles;

Fig. 6 is a bottom plan view of a shoe in process of construction provided with an insole like that shown in Figs. 1 and 2, showing the shoe upper lasted to the insole prior 45 to pulling the lasting tacks;

Fig. 7 is a cross-section on the line 7—7 in Fig. 6, showing the shoe ready for inseaming;

Fig. 8 is a bottom plan view of the same 50 after inseaming, showing the welt beaten down and trimmed ready for the outsole;

Fig. 9 is a cross-section of the same on the line 9—9 in Fig. 8;

Fig. 10 is a view similar to Fig. 9, showing the outsole attached;

Fig. 11 is a bottom plan view of a modified form of insole embodying the invention; and

Fig. 12 is a cross-section on the line 12—12 in Fig. 11.

The insole for a welt shoe as ordinarily made is channeled along its bottom edge from the heel end of the shank on one side around the toe to the heel end of the shank on the opposite side, and a lip is turned up 65 along the full length of the channel on its inner side. For the purposes of this invention the channel and lip is omitted from the inside of the shank part of the insole and may also be omitted from the outside of the 70 shank if desired.

Referring to the drawings, wherein the shoe is shown bottom up, the insole 14 shown in Fig. 1 has a channel and lip 15 extending from the heel end of the shank 75 on the outside around the toe to the shank end of the forepart on the inside. A strip 16 of leather, canvas or similar material, shaped to conform to the shank portion of the insole, is glued or otherwise secured to 80 the middle of the bottom face of the insole across its shank portion. The edges of the strip 16 are loose, and are turned up to form lips 17 conforming to the line of the inseam. The lip 17 on the outside of the shank lies 85 against the inside of the channel lip 15 of the insole, and on the inside of the shank it laps the end of the channel lip 15 at the junction of the forepart and shank and forms an extension of the lip 15 along the 90 inside of the shank back to the heel.

In Figs. 3, 4 and 5, the insole 18 is channeled around the forepart only, the shank portion being left unchanneled. In Fig. 3 the shank strip 16 is secured to the insole by 95 thin paste or small tacks sufficient to hold it in place during the process of making the shoe. In Fig. 4 the shank strip 16 is secured to the insole 18 by a line of stitching 19 which follows the outline of the outside of the shank just inside of the lip 17. In Fig. 5 the shank strip 16 is secured to the insole 18 by two lines of stitching 20, which follow the outline of the shank along both edges at a little distance inside of the 100 lips 17. In the construction shown in Figs.

3, 4 and 5 the shank portion of the sole may be trimmed somewhat closer than could be done if a channel lip were used, and the sole will lie closer to the upper.

5 The lasting and inseaming operations are performed in the same manner and with the same machines as for ordinary welt shoes; and these operations are the same for the several forms of insole illustrated in 10 Figs. 1 to 5, inclusive. In lasting, the upper 21 is pulled over the last and tacked alongside of the lips 17 of the shank strip 16 as readily as against the lip 15 of the insole (see Fig. 6), the lasting tacks 22 being driven into the last in the usual manner. The staples 23, which are set when the lasting tacks are pulled, are readily passed through the upper, insole lip 15 and shank piece lips 17 to hold them securely for 15 inseaming, as shown in Fig. 7.

The welt 24 extends from the heel end of the shank on one side around the toe to the heel end of the shank on the other side in one continuous strip, and is secured to the 25 lips 15 and 17 of the insole and shank piece by the inseam stitching 25 for its entire length in one operation, as in ordinary welt shoes. The shank ends of the counter are also secured to the ends of the lips 17 by the 30 inseaming. The inner edge of the welt is grooved and scarfed in any suitable manner for co-operating with the particular inseaming machine used. Following the inseaming, the inner edge of the welt and the 35 projecting edges of the upper and counters and the edges of the lips on the insole and shank piece are trimmed, and the welt is beaten flat, as shown in Figs. 8 and 9.

Following the inseaming, the middle portion 40 of the insole is filled with suitable filling 26, and the outsole 27 is sewed to the welt in the usual manner, as shown in Fig. 10.

The insole 28 shown in Figs. 11 and 12 is 45 channeled around the fore-part only, and in this respect is similar to the insole 18 shown in Figs. 3, 4 and 5. The shank piece 29 shown in Figs. 11 and 12 has lips 30 turned up along its side edges similar to the 50 lips 17 of the shank piece 16. The shank piece 29 is secured to the insole 28 by means of extension portions 31 at its ends which are glued or tacked to the forepart and heel of the insole, the shank portion being left 55 loose in order to provide a very flexible shank for the finished shoe, and to provide a close shank shoe.

It is evident from the foregoing description that the invention is applicable in various forms to all kinds of welt shoes, and the invention is not restricted to any particular construction shown and described above.

I claim the following as my invention:

65 1. A welt shoe comprising an insole pro-

vided with a shank piece secured to the insole along its outer edge and extending across the under side of the shank with its inner edge loose, said shank piece having lips along its edges, an upper secured to said lips, and a welt extending from the heel end of the shank on one side around the toe to the heel end of the shank on the other side and secured to said upper and lips, whereby said upper and welt are loose from said insole along the inner edge of the shank. 75

2. A welt shoe comprising an insole channeled from the heel on the outside around the toe to the shank on the inside, the shank on the inside being unchanneled and provided with a shank piece extending across the under side of the shank, said shank piece having a lip along its inside edge, an upper secured to the channeled edge of said insole, and to said lip, and a welt extending from the heel end of the shank on one side around the toe to the heel end of the shank on the other side and secured to said upper and lip. 80

3. A welt shoe comprising an insole, and a welt continuous from heel to heel inseamed 90 to the insole around the toe and fore-part and loose from the insole along the shank.

4. A welt shoe comprising an insole, a welt inseamed to the insole around the toe and fore-part and loose from the insole along the 95 shank, and a shank piece arranged across the shank under the insole to which said welt is secured.

5. A welt shoe comprising an insole channeled around the fore-part to form a lip, a 100 shank piece arranged across the shank beneath the insole and having its side edges turned down and lapping said channeled lip at the fore end of the shank and inseamed thereto, said shank piece being loose from the insole along its inside edge and secured to the insole at the heel end of the shank. 105

6. A welt shoe comprising an insole channeled around the fore-part to form a lip, a 110 shank piece arranged beneath the insole and having its edge on the inner side of the shank turned down and lapping said channeled lip at the fore end of the shank and inseamed thereto, said shank piece being secured to the insole away from its inner edge 115 whereby said downturned edge is loose from the insole under the shank.

7. A welt shoe comprising an insole channeled around the fore-part to form a lip, a shank piece arranged beneath the insole and having its edge on the inner side of the shank turned down, said shank piece being secured to the insole away from its inner edge, an upper secured to said lip and shank piece, and a welt secured to said upper, lip 120 and turned-down edge of said shank piece. 125

8. A welt shoe comprising an insole, a shank piece arranged across the shank beneath the insole and having its side edges free of said insole and turned down, and a 130

- counter lapping said shank piece and in-seamed thereto, said shank piece being secured to the insole at the fore end of the shank and free from the insole on the inner 5 side of the shank.
9. An insole for a welt shoe, said insole having a shank piece on its bottom face loose from the insole at its inner side and secured thereto at its outer side and provided with 10 downturned edges adapted to receive the inseaming.
10. An insole for a welt shoe, said insole having a lip around its fore-part and a loose shank piece on its bottom face under its 15 shank portion, said shank piece being loose from the inner side of said insole and secured thereto away from its inner side and said shank piece being provided with downturned edges forming extensions of said lip 20 and adapted to receive the inseaming.
11. An insole for a welt shoe, said insole having a lip on its under side extending from the heel end of the shank on the outside around the toe and terminating at the 25 shank end of the fore-part on the inside, and a shank piece on its under side provided with a downturned edge adapted to receive the inseaming on the inside of the shank.
12. An insole for a welt shoe, said insole 30 having a shank piece loose from its under face at the inner side and secured to its under face away from the inner side, said shank piece being provided with a downturned edge adapted to receive the inseaming.
13. An insole having a shank piece with a 35 downturned flange along its edge, said shank piece being secured to the under face of the insole away from said downturned flange,
- said downturned flange following the inner 40 side of the shank of the shoe, from which it is loose and separable, and overlapping the heel seat and fore-part of said insole.
14. The process of making welt shoes which comprises channeling the insole 45 around the fore-part, arranging a shank piece having downturned edges across the insole beneath its shank, lasting the upper to the insole, and inseaming the upper to the insole around the fore-part and inseaming 50 only to the shank piece along the inside of the shank, whereby said upper is free of the insole along the inside of the shank.
15. The process of making welt shoes which comprises channeling the insole 55 around the fore-part, arranging a shank piece having downturned edges across the insole beneath its shank, and secured thereto only along one side away from the edge, lasting the upper to the insole, and inseam- 60 ing the upper only to the insole around the fore-part and to the shank piece along the shank, whereby said upper is free of the insole along the edges of the shank and a close shank may be formed. 65
16. The process of making welt shoes which comprises arranging a shank piece under the insole, said shank piece being secured to the insole only along one side and having a lip along its edge adapted to receive the inseaming, lasting the upper to the insole, and inseaming it to said lip only, whereby when the lasting tacks are pulled said upper is free of the insole along said lip. 70

Signed at St. Louis, Missouri, this 14th day of December, 1915.

WILLIAM H. BAIN.
